UNITED STATES PATENT OFFICE.

SIGMUND GOLOMBEK, OF NEW YORK, N. Y.

CLOCK-MOVEMENT.

No. 813,644.

Specification of Letters Patent.

Patented Feb. 27, 1906.

Application filed June 3, 1905. Serial No. 263,543.

To all whom it may concern:

Be it known that I, SIGMUND GOLOMBEK, a citizen of Russia, residing at New York city, (Manhattan,) county and State of New York, 5 have invented new and useful Improvements in Clock-Movements, of which the following is a specification.

This invention relates to a clock-movement in which a single mainspring operates 10 the hands, the striking mechanism, and the alarm mechanism in such a way that the various functions thus assumed by the spring may be independently and properly performed.

15 The invention may also be applied to watch-movements.

Briefly stated, the invention consists in providing a clock with a single spring which by a common train of gears operatively connected to one end of said spring actuates the hands and the striking mechanism, while another set of gears operatively connected to the other end of the spring actuates the alarm. It is evident that the spring will 20 wind more rapidly during the striking of the clock than during the period in which the hands are moved. As the common train of gears also runs faster while the clock strikes, means are provided which uncouple said 25 train when the clock strikes from the usual connection with the escapement and from the hands. The latter will thus be at rest while the clock strikes. As soon as the striking is completed the hands and the usual connection with the escapement are recoupled to 30 the train of gears, which will thus run at normal speed until the next striking.

The construction will be more fully understood from the accompanying drawings, in 40 which—

Figure 1 is a front view of my improved clock; Fig. 2, a rear view thereof; Fig. 3, a front view of the clock-movement with some of the parts omitted. Figs. 4, 5, and 5^a are details of the strike-controlling mechanism, showing the parts in different positions; Fig. 5^b, a detail of the sector-setting lever; Fig. 6, an enlarged side view of the clock-movement with some of the parts omitted; Fig. 6^a, a 45 similar view of part of the same, showing the parts in a different position; Fig. 7, a detail rear view of the hammer-operating means; Fig. 8, a detail of part thereof, showing the parts in a different position; Fig. 9, a detail of 50 the shipping-lever; Fig. 10, a detail of the finger-carrying wheel; Fig. 11, an end view of

Fig. 10; Fig. 12, a plan of Fig. 6 with some of the parts omitted; Fig. 13, a detail front view of the train of gears for operating the hands; Fig. 14, a side view thereof; Fig. 15, a detail 60 front view, partly in section, of the train of gears for operating the striking mechanism; Fig. 16, a side view thereof; Fig. 17, a detail front view, partly in section, of the train of gears for operating the alarm; and Fig. 18, a 65 side view thereof.

The letter *a* indicates the casing of a clock, the front of which is provided with the dial *a'* and with hands *a²* *a³* *a⁴* in the usual manner. Within the casing *a* there is contained the 70 mainspring *b*, the inner and outer ends of which are secured to toothed wheels *b'* *b²*, respectively. Of these the first wheel *b'* operates the mechanism for moving the hands and striking the hours, while the second wheel *b²* operates the alarm. Wheel *b'* engages a lantern-wheel *c'*, fast on a hollow spindle *c*, that in turn transmits motion by a toothed wheel *c²* to a pinion *c³*, fast on an arbor *c⁴*, carrying a pinion *c⁵*. This pinion drives a wheel 80 *d*, fast on an arbor *d'*, which is free to turn within tubular spindle *c*. The arbor *d'* turns once every hour and has a reduced end *d⁶*, to which the minute-hand *a³* is fastened. Fast on arbor *d'* is a pinion *d³*, that engages a wheel 85 *e'*, loosely mounted within a bracket *a¹⁰* of frame *a*. To wheel *e'* is secured a pinion *e¹⁰*, which engages a toothed wheel *e¹¹*, fast on a tubular shaft *e¹²*, loosely mounted upon spindle *d'*. Shaft *e¹²* has a reduced front end 90 *e¹³*, to which the hour-hand *a²* is secured. Wheel *d*, that turns once every hour with arbor *d'*, is mutilated, as at *d²*, by having two adjoining teeth removed, so that wheel *d* will not be taken along by pinion *c⁵* when the mutilated section *d²* arrives opposite the pinion. During this period of rest the hands *a²* *a³* are 95 also at rest, as they are operated by wheel *d* and spindle *d'*.

Intermediate wheel *d* and pinion *d³* there is 100 loosely fitted upon arbor *d'* a pinion *e*, that engages wheel *e'*. Pinion *d³*, that operates wheel *e'*, as above stated, is provided with eleven teeth, while pinion *e* is provided with twelve teeth. As both pinions *d³* *e* engage 105 the same wheel *e'*, a differential movement is thus imparted to pinions *d³* *e*—that is, pinion *e* will fall back for exactly one tooth at each complete rotation of pinion *d³* and wheel *d*. This differential movement is used for 110 regulating the number of strokes, so that they conform to the different hours in the fol-

lowing manner: To pinion e is secured a snail or cam disk e^2 , provided with twelve steps that successively decrease in radius. The first step e^{14} of the largest radius is connected to the last step e^{15} of the smallest radius by an approximately radial edge e^{16} . The steps are adapted to be engaged by the bent end e^3 of a curved lever e^3 . This lever is pivoted to wheel d at e^4 and is pressed toward the snail by a spring e^5 . The other end of lever e^3 has a pin e^6 , which is received by a radial slot f' of a toothed sector f . The latter turns loosely on arbor d' and is interposed between wheel d and disk e^2 . The radius of wheel d is equal to that of the sector, and the pitch of the teeth on both is alike, so that pinion c^5 is adapted to engage wheel d and sector f . As thus far described, it will be seen that at each complete rotation of wheel d to the arbor d' of which the minute-hand is secured, pinion e will fall back for exactly one tooth—i. e., one-twelfth of a complete rotation. Cam-disk e^2 , being secured to pinion e , will also be retarded for one-twelfth of a rotation—i. e., for the length of one step. This rotation of snail e^2 in relation to wheel d is utilized for setting sector f , that controls the number of strokes of the hammer. The relative position of wheel d , sector f , and lever e^3 is such that when lever e^3 engages the step e^{14} of the largest diameter one tooth of wheel d will be exposed between the end of sector f and a pin d^4 , secured to wheel d , Fig. 5. This position of sector f relative to mutilated wheel d allows the gong to strike once to announce one o'clock time. The mechanism for said sounding of the gong will be hereinafter described.

During the hour succeeding the striking the hook e^{17} will ride along step e^{14} until the hook arrives opposite the adjoining step e^{18} . The parts are so adjusted that hook e^{17} arrives opposite the succeeding step e^{18} before the full hour has elapsed. Spring e^5 , by pressing upon lever e^3 , will slightly tilt the latter on pivot e^4 . This tilting of lever e^3 results in a partial rotation of sector f in relation to wheel d . As will be readily understood from Fig. 5, pin e^6 of lever e^3 will be slightly swung up as soon as hook e^{17} leaves step e^{14} and engages step e^{18} . The slight upward movement of pin e^6 will by the engagement with slot f' of sector f rotate the latter for the length of exactly one tooth. In this way two teeth will become exposed or be left uncovered between the end of the sector and pin d^4 . It will thus be seen that as soon as hook e^{17} passes from one step to another (which movement takes place once during every hour) the number of teeth exposed between sector f and pin d^4 will be increased by one tooth. After twelve hours have elapsed hook e^{17} will gradually pass from the position shown in Fig. 5 to the position shown in Fig. 4, when said hook will engage the smallest step e^{15} . In this position twelve teeth are left uncovered between sec-

tor f and pin d^4 , so that the gong will be sounded twelve times in manner hereinafter described.

For the sake of greater clearness it may be stated that the position of snail e^2 in relation to wheel d determines the position of sector f upon wheel d , while sector f , in connection with wheel d , controls the number of strokes of the hammer.

The striking operation takes place as soon as the mutilated section d^2 of wheel d arrives opposite pinion c^5 . As sector f is so arranged above wheel d —that is, can only play between the two end positions shown in Figs. 4 and 5—it will be seen that the mutilated section d^2 of wheel d is always covered by sector f . When said mutilated section of wheel d and the sector f arrive opposite pinion c^5 , wheel d will be arrested, while sector f will alone be rotated in the direction of the arrow, Fig. 4, until it bears against stop-pin d^4 , and thus takes wheel d along. After a slight rotation imparted to wheel d by sector f the tooth adjoining the mutilated section of wheel d will engage pinion c^5 , so that the latter will now again turn the wheel for one complete rotation, corresponding to the lapse of one hour, when the mutilated section will again arrive opposite pinion c^5 to cause the hammer to strike the next hour. It will be observed that during said rotation of wheel d hook e^{17} has passed from one step of snail e^2 to the next step, so as to change the position of sector f relative to wheel d .

As has already been stated, wheel d and sector f control the striking mechanism in such a manner that the hammer strikes once for every dental movement of sector f upon wheel d . The means for effecting this result are as follows: An axially-movable shaft g is rotated from arbor c^4 by wheel c^6 and lantern-wheel g' . Spindle g carries a wheel g^2 , that is adapted to engage a pinion g^3 , operating an escapement G of any suitable construction. The shaft g is axially displaceable in manner hereinafter described by wheel d to disengage wheel g^2 from escapement-pinion g^3 while the clock is striking. Wheel g^2 has a radial finger g^4 , having at its outer end a tooth g^{20} , which is of the same size as the teeth of wheel g^2 and which is in alinement with one of such teeth. This tooth intermittently engages pinion g^3 when wheel g^2 is rotating, but without then performing any work. After shaft g has been shifted to the right, Fig. 6, in manner hereinafter described wheel g^2 is out of engagement with pinion g^3 , while the tooth g^{20} of finger g^4 is still adapted to engage pinion g^3 and to permit intermittent rapid consecutive rotations of shaft g whenever the parts g^2 g^3 are thrown out of gear. The parts are so set that shaft g is shifted laterally, while tooth g^{20} of finger g^4 is in engagement with pinion g^3 . As soon as during the continuing rotation of wheel g^2 and finger g^4 the

latter clears pinion g^3 the tension of spring b will cause shaft g , together with wheel g^2 and finger g^4 , to make a rapid rotation until tooth g^{20} reengages pinion g^3 . This rapid movement requires but a very short time, so that the escapement G , owing to its momentum, is still in motion when tooth g^{20} reengages pinion g^3 after having performed said rapid rotation. The tooth g^{20} , and consequently shaft g , is now retarded while contacting with the rotating pinion g^3 of the escapement, while after clearing the same it will make an additional rapid rotation until it is again retarded by being thrown into engagement with pinion g^3 . Each rapid rotation of shaft g causes, by parts $g' c^6$, a corresponding rapid and partial rotation of arbor c^4 and pinion c^5 . The parts are so proportioned that each rapid rotation of shaft g will advance pinion c^5 for the length of one tooth, while they are so timed that said rapid rotation takes place after the hands have stopped—i. e., after the mutilated section d^2 of wheel d has arrived opposite pinion c^5 . In this position of the parts sector f only, and not wheel d , is in engagement with pinion c^5 . It will thus be readily understood that each complete rapid rotation of shaft g will advance sector f for one tooth when pinion c^5 is advanced for one tooth. The number of consecutive rapid rotations which shaft g is allowed to make depends upon the position of sector f , which in turn depends upon the position of snail e^2 . If, for instance, twelve teeth are exposed between sector f and pin d^4 , Fig. 4, shaft g will be allowed to make twelve rapid rotations. After the twelfth rotation sector f contacts with pin d^4 , so that the sector will take along wheel d to restart the hands.

Each rapid rotation of shaft g causes one stroke of the hammer in the following manner: Upon shaft g is mounted a crank-pin g^5 , which when shaft g is shifted to the right, Fig. 6^a, is thrown across the path of a lever h' , mounted by pin h^2 upon a rock-shaft h . The rock-shaft h is influenced by a spring h^3 and carries the hammer h^4 . Each rotation of shaft g when the latter is shifted will therefore, by lever h' and shaft h , swing the hammer h^4 to execute one stroke of the gong. It will thus be seen that the number of teeth of wheel d which are exposed between sector f and pin d^4 determines the number of rapid rotations of shaft g and that each of such rotations causes one stroke of the hammer.

To operate shaft g , I employ a three-arm lever $i' i^2$, pivoted at i^3 . Arm i of such lever is engaged by the arm j^{10} of a shipping-lever j , pivoted at j' and operated in manner hereinafter described. Arms $i' i^2$ are provided at their free ends with plates $i^{11} i^{12}$, that rest against the left and right ends of shaft g , respectively. When arm j^{10} is raised, it will by bearing against arm i of lever $i' i^2$ turn said lever to the right—i. e., from the position

shown in Fig. 6 to that shown in Fig. 6^a. Plate i^{11} of lever-arm i' will during this movement take spindle g along and shift it to the right, Fig. 6^a, in order to disengage wheels $g^2 g^3$ and to bring crank g^5 into the path of hammer-lever h' , as hereinabove referred to. End plate i^{12} is influenced by a spring i^4 , which tends to turn lever $i' i^2$ to the left. After the shipping-lever j has been released in manner hereinafter described spring i^4 will turn lever $i' i^2$ to the left. During this movement shaft g will also be shifted to the left, Fig. 6, by the engagement of the right end of shaft g with end plate i^{12} , so as to reengage parts $g^2 g^3$ and to withdraw crank g^5 from the path of lever h' . The turning movement of lever $i' i^2$ also causes arm i to be depressed and to thereby return lever j to its normal position.

The shipping-lever j is operated in the following manner: To wheel d is pivoted, by projecting pin k' , a bent lever k , having pin k^2 near its angle. The pin k^2 is adapted to engage a finger j^2 , pivoted to lever j at j^3 and normally held off the same by spring j^4 . The parts are so positioned that when the mutilated section d^2 of wheel d approaches pinion c^5 pin k^2 will bear upon finger j^2 , and thereby swing the latter toward lever j and compress spring j^4 . During this operation lever j is held against displacement by a pair of pins d^5 , projecting from wheel d and adapted to successively engage an arched collar j^5 of lever j . Pins d^5 are so positioned that when the mutilated section of wheel d is opposite pinion c^5 the pins d^5 will clear collar j^5 and permit the spring j^4 to rapidly tilt lever j , so as to raise arm i , and consequently shift shaft g in manner hereinabove described. In this depressed position of lever j a transverse groove j^6 of the latter will be projected over pin k' , and thereby lock wheel d against rotation. In this way any rotation of wheel d during the movement of sector f is prevented. When the sector f is about to complete its independent movement, a beveled arm f^2 of the same will bear against free end k^3 of lever k and tilt the same, so that pin k^2 is disengaged from finger j^2 . The lever j being thus released will, together with shaft g , be returned to its normal position by spring i^4 to arrest the striking mechanism and restart the hands.

To cause the striking mechanism to be released only when the crank g^5 is in the proper position with relation to lever h' for striking said lever during its rotation, there is fulcrumed to the frame a at l' an elbow-lever l . One arm of this lever terminates in an elliptical eye l^2 , which is engaged by crank g^5 , so that in this way the crank imparts an oscillating movement to the lever l . The second arm of this lever is notched, as at l^3 , to engage a pin j^7 of lever j . Thus when the crank g^5 swings eye l^2 downward notch l^3 will re-

lease pin j^7 to liberate lever j , Fig. 7, while when eye l^2 is swung up by crank g^5 lever j will be locked.

The operation of the above-described mechanism for moving the hands and striking the hours is as follows: Assuming the parts to be in a position shortly prior to that shown in Fig. 4, wheel d is slowly rotated by pinion c^5 to operate the hands in the usual manner. When it is exactly twelve o'clock, mutilated section d^2 of wheel d has arrived opposite pinion c^5 , so that wheel d , and consequently the hands, will not move until the twelve strokes have been given by the hammer. Before the parts assumed the position shown in Fig. 4 pin k^2 has pressed finger j^2 toward lever j , the latter being held against displacement by pins d^5 . As soon as the mutilated section d^2 has arrived opposite pinion c^5 the lower pin d^5 , Fig. 7, will have cleared collar j^5 of lever j . Spring j^4 will therefore rapidly turn the lever j to raise its arm j^{10} , and thereby turn lever $i^1 i^2 i^3$ to the right, so as to shift shaft g correspondingly, Fig. 6^a. In this way parts $g^2 g^3$ are disengaged and shaft g is allowed to make twelve consecutive rapid rotations, as twelve teeth are exposed between sector f and pin d^4 . At each rotation of shaft g the gong is sounded once by the engagement of crank g^5 and lever h' and the sector f is advanced for the distance of one tooth, wheel d being arrested by the engagement of the parts $j^8 k^1$. The gradual advancement of sector f will gradually turn lever e^3 on its pivot e^4 by the engagement of slot f' and pin e^6 . At the twelfth stroke lever e^3 will have assumed the position shown in Fig. 5^a. During the twelfth or last stroke of the clock beveled arm f^2 of sector f bears against the free end k^3 of lever k and tilts the same, so that pin k^2 is disengaged from finger j^2 . The lever j being thus released will also release lever $i^1 i^2 i^3$. Spring i^4 will thus be permitted to turn said lever $i^1 i^2 i^3$ to the left in order to reengage parts $g^2 g^3$ and to bring crank g^5 out of the path of lever h' . The rotation of lever $i^1 i^2 i^3$ will by the engagement of parts $i^1 j^{10}$ swing lever j into its normal position, Fig. 8. After the last stroke of the clock sector f engages pin d^4 of wheel d , and as parts $g^2 g^3$ are reengaged by the shifting of shaft g to the left sector f will be slowly rotated, whereby it takes wheel d along, so that the teeth of wheel d reengage pinion c^5 . In this way the hands are restarted immediately after the striking is over. Sector f and wheel d will now jointly engage pinion c^5 , so that the latter will now turn the sector, as well as the wheel. After the last tooth of sector f has cleared pinion c^5 spring e^5 by pressing upon lever e^3 will hold the sector against rotation until the latter has fallen back for the length of one tooth. After the sector has thus been retarded for such dis-

tance hook e^{17} will rest upon step e^{14} of snail 6^5 e^2 , and thereby prevent the sector from further falling back. The continued rotation of pinion c^5 will now rotate wheel d and sector f jointly until at one o'clock the mutilated section d^2 has again arrived opposite pinion c^5 , and the operation just described is repeated; but as there is now only one tooth exposed between sector f and pin d^4 , Fig. 5, the gong will be sounded only once, thus indicating the hour of one o'clock. As the snail e^2 is retarded at each rotation of wheel d for one step the lever e^3 by engaging a new step will add a tooth to the number of teeth previously exposed between sector f and pin d^4 until the hour of twelve o'clock, when the lever e^3 is lifted from the twelve-o'clock step e^{15} to the one-o'clock step e^{14} by the engagement of pin e^6 of lever e^3 with slot f' of sector f .

The alarm is sounded by the same hammer h^4 which sounds the hours. It is operated by the usual notch disk m , which releases a spring-lever m' , the upper bent end of which is thus drawn out of the path of lever h' , and thus permits the vibration of shaft h , and consequently of hammer h^4 . The alarm is arrested by a pin b^3 of ratchet-wheel b^4 , which is used in winding up the spring. Pin b^3 upon the full rotation of wheel b^2 contacts with a pin n' of a ratchet-wheel n , loosely mounted on spindle b^5 of wheel b^2 . Thus wheel n is taken along by wheel b^2 and will by bearing against a nose o' of a lever o , fulcrumed at o^2 , swing said lever upward. Lever o will thus tilt a lever p on fulcrum p' , and thereby project a stop p^2 of said lever over a finger q' of spindle q , so that the latter is arrested. Spindle q receives motion from wheel b^2 by lantern-wheel r' , shaft r , wheel r^2 , and pinion q^3 . It carries the wheel q^2 , that vibrates rock-shaft h by double pawl h^5 in the usual manner.

It will be seen that in my improved clock-movement the hands, striking mechanism, and alarm are all actuated by one and the same mainspring and that the hands and the striking mechanism are operated by a common train of gearing in such a manner that the hands are arrested while the hammer is actuated, and vice versa.

It is obvious that the hands lose a small part of time as they are arrested during the striking operation of the clock. This must be compensated for by correspondingly regulating the escapement-spring.

As the spring unwinds most rapidly during the striking of the clock, the latter will by the construction described be prevented from going too fast while it strikes, and the spring is thereby permitted to properly fulfil its dual functions.

What I claim is—

1. A clock-movement provided with a mainspring, hands, a hammer, and means for

alternately operating the hands and hammer by the same end of said spring, substantially as specified.

2. A clock-movement provided with a mainspring, hands, a hammer, means for alternately operating the hands and the hammer by said spring, and means for arresting the hands while the hammer is actuated, substantially as specified.

10 3. A clock-movement provided with a mainspring, hands, a hammer, a train of gearing actuated by said spring, and means operated by said train for alternately actuating the hands and the hammer, substantially as specified.

15 4. A clock-movement provided with a mainspring, hands, a hammer, a pinion operated by said spring, a mutilated toothed wheel engaged by the pinion and adapted to operate the hands, and a toothed sector also engaged by the pinion and controlling the hammer, substantially as specified.

20 5. A clock-movement provided with a mutilated toothed wheel, a pin on said wheel, a toothed sector adapted to engage said pin, and means for rotating the wheel and sector, substantially as specified.

25 6. A clock-movement provided with a mutilated toothed wheel, a pin on said wheel, a toothed sector adapted to engage said pin, means for changing the relative position between wheel and sector, and means for rotating the wheel and sector, substantially as specified.

30 7. A clock-movement provided with a mutilated toothed wheel, a pin on said wheel, a toothed sector adapted to engage said pin, a stepped disk, a lever engaged thereby and operatively connected to the sector, and means for imparting different speed to the wheel and disk, substantially as specified.

35 8. A clock-movement provided with an escapement, a hammer, an axially-movable shaft, a toothed wheel and a finger on said shaft adapted to engage the escapement, means on the shaft for operating the hammer, and means for axially moving the shaft, substantially as specified.

40 9. A clock-movement provided with an escapement, hands, a hammer, an axially-movable shaft, a toothed wheel and a finger on said shaft adapted to engage the escapement,

means on the shaft for operating the hammer, a hand-operating wheel, and means controlled by said wheel for axially moving the shaft, substantially as specified.

45 10. A clock-movement provided with an escapement, hands, a hammer, an axially-movable shaft, a toothed wheel and a finger on said shaft adapted to engage the escapement, means on the shaft for operating the hammer, a hand-operating wheel, a shipping-lever operatively connected thereto, and means controlled by said lever for axially moving the shaft, substantially as specified.

50 11. A clock-movement provided with hands, a hammer, a hand-operating wheel, a shipping-lever operatively connected thereto, an axially-movable shaft operatively connected to said lever, a crank on the shaft adapted to actuate the hammer, and an elbow-lever controlled by the crank and adapted to engage the shipping-lever, substantially as specified.

55 12. A clock-movement provided with hands, a hammer, a hand-operating wheel, a shipping-lever operatively connected thereto, an axially-movable shaft operatively connected to said lever, a crank on the shaft adapted to actuate the hammer, an elbow-lever having an eye engaged by the crank, and a notched arm adapted to engage the shipping-lever, substantially as specified.

60 13. A clock-movement provided with a mainspring, hands, a striking mechanism, an alarm mechanism, and means for operating the hands, the striking mechanism and the alarm mechanism by said spring, substantially as specified.

65 14. A clock-movement provided with a mainspring, hands, a striking mechanism, a first toothed wheel operated by said spring and adapted to actuate the hands and striking mechanism, a second toothed wheel also operated by said spring, an alarm mechanism, and means for operating said alarm mechanism by said second toothed wheel, substantially as specified.

70 Signed by me at New York city, (Manhattan,) New York, this 2d day of June, 1905.

100 SIGMUND GOLOMBEK.
